US00D956967S

(12) **United States Design Patent** (10) **Patent No.:** **US D956,967 S**
(45) **Date of Patent:** **** Jul. 5, 2022**

(54) **MANIFOLD HOUSING FOR A MEDICAL WASTE COLLECTION DEVICE**

(71) Applicant: **Stryker Corporation**, Kalamazoo, MI (US)

(72) Inventor: **Michael Zollinger**, Chelsea, MI (US)

(73) Assignee: **Stryker Corporation**, Kalamazoo, MI (US)

(**) Term: **15 Years**

(21) Appl. No.: **29/781,723**

(22) Filed: **Apr. 30, 2021**

(57) **CLAIM**

The ornamental design for a manifold housing for a medical waste collection device, as shown and described.

DESCRIPTION

FIG. 1 is a rear, top, left side perspective view of a manifold housing for a medical waste collection device;

FIG. 2 is another rear, top, left side perspective view thereof;

FIG. 3 is a front, bottom, right side perspective view thereof;

FIG. 4 is a left side perspective view thereof;

FIG. 5 is a front, bottom perspective view thereof;

FIG. 6 is a rear, bottom perspective view thereof;

FIG. 7 is a left side view thereof;

FIG. 8 is a right side view thereof;

FIG. 9 is a rear view thereof;

FIG. 10 is a front view thereof;

FIG. 11 is a top view thereof; and,

FIG. 12 is a bottom view thereof.

The dotted broken lines in the drawings depict portions of a manifold housing for a medical waste collection device that form no part of the claimed design.

1 Claim, 11 Drawing Sheets

Related U.S. Application Data

application No. 29/712,742, filed on Nov. 11, 2019,
now Pat. No. Des. 919,799.
